UNITED STATES PATENT OFFICE.

JOSEPH W. HORTON, OF EAST ORANGE, NEW JERSEY, ASSIGNOR TO WESTERN ELECTRIC COMPANY, INCORPORATED, OF NEW YORK, N. Y., A CORPORATION OF NEW YORK.

CARRIER-WAVE SIGNALING SYSTEM.

Application filed March 18, 1922. Serial No. 544,709.

To all whom it may concern:

Be it known that I, JOSEPH W. HORTON, a citizen of the United States, residing at East Orange, in the county of Essex, State of New Jersey, have invented certain new and useful Improvements in a Carrier-Wave Signaling System, of which the following is a full, clear, concise, and exact description.

The present invention relates to high frequency or carrier wave signaling in which carrier waves of a plurality of frequencies are employed.

The invention is particularly applicable to systems in which carrier waves of different frequencies are used for transmission in opposite directions.

A feature of the invention is the arrangement by which a single translating circuit is made to oscillate at two distinct carrier wave frequencies both of which are employed for signaling.

More specifically the translating circuit of the invention comprises a vacuum discharge tube modulator-demodulator arranged to oscillate at two distinct carrier frequencies, the carrier wave of one frequency being used to transmit signals, and the wave of the other generated frequency being combined with received carrier waves to enable reception of the signals. The generated wave used in signal reception is preferably of the same frequency as the carrier wave, the modulations of which represent the signals to be received.

The oscillator-modulator-demodulator of the invention is preferably of a balanced circuit type arranged to suppress transmission of each carrier wave but to produce and transmit the side-band components resulting from the impression of signaling voltage variations thereon. These signaling waves or variations comprise both the received side-band components from a distant station, which combine with the generated wave of the proper frequency in accordance with the well-known homodyne action to enable reception of the signals, and low-frequency signal waves such for example as speech current waves which modulate the carrier wave of the transmitting frequency to produce side bands for transmission to the distant station. Suitable filters are connected between the translating circuit and the high frequency terminal to prevent return of the

outgoing side band components to the receiving side of the translating circuit.

The invention is applicable particularly to a carrier current system having a single or a plurality of two-way channels each employing different transmitting and receiving frequencies, and the invention will be described below as embodied in a terminal circuit for such a system, as a monitoring circuit for a mid-line repeater station in such a system, and as a portable set for use in such a system. The various features and objects of the invention will be clear from the following detailed description in connection with the drawings showing diagrammatically the three mentioned specific applications of the invention to a multiplex carrier line, Fig. 1 showing the application to a terminal circuit; Fig. 2 to a monitoring circuit for a mid-line repeater; and Fig. 3 to a portable signaling circuit.

The line ML is a multiplex carrier transmission line having the channel apparatus arranged so that the channels used for transmission in one direction employ frequencies grouped in one frequency range, while the channels used for transmission in the opposite direction have their frequencies grouped in a different range. It will be assumed that the channels transmitting over the line ML to the right in Figs. 1 and 2 employ frequencies from 23,333 cycles upwards, while the channels transmitting to the left employ frequencies from 20,000 cycles downward.

Referring now to Fig. 1 terminal circuits for two carrier channels C¹ and C² cooperating with two low frequency lines LL¹ and LL² respectively are indicated. Other channels may be added to the line ML in a similar manner as may be desired. It is assumed in the present instance that the carrier waves for the entire system are multiples of 3,333 cycles although any other suitable frequency scheme may be used and if desired the frequency spacing between carriers may be non-uniform. The channel C¹ is indicated as employing a carrier frequency of the third multiple or 10,000 cycles for receiving from the line ML, while channel C² employs the fourth multiple or harmonic, a frequency of 13,333 for receiving. Each of these channels uses the lower side band for reception. For transmission these

2

channels use respectively 23,333 or the seventh harmonic and 26,666 or the eighth harmonic and are arranged to transmit the upper side bands. Receiving band filters 5 BF¹ and BF³ arranged to pass the respective receiving frequencies and transmitting filters BF² and BF⁴ designed to pass the corresponding transmitting frequencies serve to connect the respective channels C¹ and C² 10 with the main line. These and the other filters indicated throughout the system may be designed in accordance with the principles disclosed in the patent to G. A. Campbell, No. 1,227,113, granted May 22, 1917.

15 Except for the frequencies which they employ, channels C¹ and C² may be duplicates of each other, and it will suffice to describe the circuit of channel C¹. The filter BF¹ leads to a common input circuit 10 of 20 the translating circuit OMD¹ while the output side of this translating circuit is connected to a common outgoing circuit 11 leading to the transmitting filter BF². The circuits 10 and 11 are connected through low 25 pass filters LP¹ and LP² with the line LL¹, through the usual duplex connection comprising the three-winding repeating coil H¹ and the line balancing network N¹. The filters LP¹ and LP² are designed to pass 30 freely currents of the frequencies employed by the line LL¹ such as speech frequencies but to oppose transmission of the carrier current.

35 The translating circuit proper included between the common incoming and outgoing circuits 10 and 11 consists of a combined oscillator-modulator-demodulator circuit arranged to oscillate simultaneously at frequencies of 10,000 cycles and 23,333, these 40 being the frequencies of the carrier waves used by the channel C¹. The common translating circuit is shown as comprising a balanced vacuum tube circuit including the two vacuum discharge tubes 12 and 13 which 45 may be of the usual cathode-grid-anode type. The filaments of these tubes are connected together and to the mid-point of the secondary of the input coil 14, the grids of these tubes being connected to respective 50 terminals of the secondary winding of this coil. The common cathode terminal of the tubes is connected through a tuned feed back circuit 15 and regulating resistance 16 to the midpoint of the primary of the output 55 transformer 17 and similarly through the tuned feed back circuit 18 and regulating resistance 19 to the same point of the output primary winding. The anodes of the two tubes are connected to the respective 60 terminals of the primary winding of the output coupling 17 through the large condensers 20-21, the space current being supplied to these anodes from the source indicated, through the respective chokes 22 65 and 23. The common portion of the grid

circuits included between the cathodes and the input coil contains a secondary winding 24 coupled to the feed back circuit 15, a secondary winding 25 coupled to the feed back circuit 18, and if desired may contain 70 a grid resistance 26 and a grid battery as indicated.

It is a characteristic of a balanced circuit of the type indicated that the outgoing coil 17 and also the input coil 14 are balanced as to voltages applied to the common portion 24, 25, 26 of the grid circuit, provided of course, that the tubes and the rest of the circuit are properly balanced. Similarly the connections between the common 80 cathode connection and the mid-point of the primary winding of coil 17 including in one case the tuned circuit 15 and in the other case the tuned circuit 18 are neutral with respect to the circuits 10 and 11. However, voltage variations impressed on the common portion 24, 25, 26 of the grid circuit are repeated in amplified form into the two anode branches 15, 16 and 18, 19. By tuning the circuit 15 to one frequency, say 10,000 cycles and the circuit 18 to a different frequency, for example, 23,333, the translating circuit may be made to oscillate independently at both of these frequencies, since output energy in the tuned circuits is returned 90 in part to the input branch which is so related to the rest of the circuit as to exercise control over the anode current supplying the feed back circuits. Since the path which the oscillations follow is as above stated 100 neutral with respect to the circuits 10 and 11, the waves locally generated are confined to the translating circuit and are prevented from passing into either circuit 10 or 11.

In addition to serving as a generator of oscillations, the common translating circuit OMD¹ also serves to modulate the transmitted carrier wave and to detect or demodulate the received carrier wave employed by the channel C¹. The operation 105 of the circuit in these two manners will be clear from following the path taken by currents in the course of transmission and reception, the operation of the translating circuit as an oscillator having already been 110 described.

115 Signaling currents such as speech currents received from the telephone line LL¹ pass through the filter LP¹ to the circuit 10, but are prevented from reaching the line ML on account of the filter BF¹ which has a transmission range above that of the filter LP¹. Speech currents are impressed on the input coil 14, causing the potentials of the grids of the tubes 12 and 13 to vary in an 120 opposite manner to each other and producing complementary impedance variations in the tubes 12 and 13. In this manner the translating circuit is unbalanced to an extent depending on the amplitude of the im- 125

pressed potential and each of the waves generated by the circuit is transmitted to the outgoing circuit 11 to an extent substantially proportional to the impressed voltage variation. As long as speech currents are impressed on the coil 14, two modulated high frequency waves are thus produced in the outgoing circuit 11. The modulated wave produced by the combination of the voice waves with the generated wave of 10,000 cycles is dissipated in the circuit 11 and does not find its way to either the lines LL¹ or ML on account of the filters LP² and BF². Assuming that the principal component frequencies of speech do not exceed an upper limit of about 2200 cycles, the modulated wave components due to the modulations of the generated wave of frequency 23,333 by the impressed voice comprise an upper side band and a lower side band made up principally of frequencies comprising respectively a range from near the carrier frequency to a frequency about 2200 cycles lower than the carrier frequency and a range from near the carrier frequency to a frequency about 2200 cycles higher than the carrier frequency. The band filter BF² is arranged to pass only the upper of these two side bands and the upper side band of the outgoing carrier frequency is in this manner impressed on the line ML.

It is assumed that the distant station is a duplicate of the station shown in Fig. 1 except that the channel C¹ at that station is arranged to receive and to transmit currents of the same frequencies that are respectively transmitted and received by the channel C¹ of the station under consideration. Under these conditions the distant station will transmit to the line ML a voice-modulated wave frequency of 10,000 cycles in a manner entirely similar to that described in connection with the channel C¹ of Fig. 1 for transmitting the upper side band of the carrier 23,333. The wave so impressed on the line ML at the distant station and received at the terminal shown in Fig. 1 is selectively transmitted by the filter BF¹ into the circuit 10 but is prevented from being transmitted by any of the other filters. The received side band is prevented by the filter LP¹ from reaching the line LL¹ but is impressed on the input coil 14. These impressed waves interact with the waves generated in the common translating circuit OMD¹ and in accordance with the well-known homodyne action, if the generated wave having a frequency of 10,000 is in synchronism with the carrier wave which was modulated in the distant station, currents of the same form as the modulating currents at the distant station will be reproduced in the outgoing circuit 11. The interaction of the received side band components with the generated wave of 23,333 will however not

produce currents within the range of either the voice filter LP² or band filter BF², and such currents are dissipated in the local circuit 11. The voice currents resulting from the detecting or demodulating of the common translating circuit as described, pass through the filter LP² and are impressed on the telephone line LL¹.

The repeating coil H², the balancing network N², the low pass filters LP and the common translating circuit OMD² of the channel C² correspond to similarly designated elements of the channel C¹ and operate in an entirely similar manner except that the waves generated in the circuit OMD² have in this case frequencies of 13,333 and 26,666 respectively.

In Fig. 2 the line ML, which may be the same line as that indicated in Fig. 1, is shown divided into two sections between which are inserted two one-way repeaters ER and WR for amplifying the waves transmitted in the respective directions over the line. The repeater ER is connected to the west section by the high pass filter HP¹ and to the east section by a similar filter HP². Similarly low pass filters LP¹ and LP² having suitable transmission range direct westward transmissions between the line sections through the repeater WR.

The common translating circuit OMD³ inserted between the incoming and outgoing circuits 30 and 31 respectively may be entirely similar to the circuit OMD¹ which would in practice have a fixed frequency setting, whereas the circuit OMD³ is intended to have the frequencies of the waves which are generated readily adjustable, as by means of the condensers 32 and 33. The operator's set, comprising a transmitter T, receiver R and appropriate connections therefor, is connected to the balanced three-winding repeating coil H³, to the other side of which the balancing network N³ is provided. The coil H³ is connected through voice filters LP³ and LP⁴ to the circuits 30 and 31 in the same way that the line LL¹ of Fig. 1 is connected to the circuits 10 and 11. The circuit 30 terminates in the plug 35 of the twin plug P¹ and also in plug 36 of the twin plug P². The incoming circuit 31 is similarly connected to the plugs 38 and 39. Channel taps terminating in jacks J are provided for some or all of the channels at the repeater station, these jacks being connected to the line ML through channel filters BF¹, BF² etc.

The operation of the circuit of Fig. 2 is as follows. If it is assumed that the attendant at the repeater station desires to communicate over channel C¹ for example, he will insert the plug P¹ so that plug 38 connects with the associated jack leading to the filter BF² and the plug 35 connects to the filter BF¹, and he inserts plug P² so that plug 36 makes connection with the associated filter

BF² and plug 39 connects with the associated filter BF¹. He then adjusts the condensers 32 and 33 so that the circuit OMD³ generates waves of the carrier frequencies used by the channel C¹, that is, 10,000 and 23,333 cycles. Transmission originating in channel C¹ of the station of Fig. 1 and employing a carrier of 23,333 passes selectively through the filter BF² of Fig. 2, terminals 10 of plug 38, incoming circuit 31 to the common translating circuit OMD³ where it interacts with the locally generated wave of the carrier frequency to produce speech currents in the outgoing circuit 30. These 15 speech currents pass through the filter LP³ to the receiver R of the attendant's telephone. A transmission originating in channel C¹ to the right of Fig. 2 passes selectively into the band filter BF¹ shown to the right 20 of the repeater, terminals of plug 39, incoming circuit 31 and common translating device OMD³ where the receiving currents interact with the locally generated wave of the carrier frequency and produce speech currents 25 in the circuit 30. These are received as before on the attendant's set.

If the attendant desires to talk in either direction over the line ML through the channel C¹, having first adjusted the condensers 32 and 33 as required by this channel, he speaks into the transmitter T of his set, the speech currents pass through the coil H³ and the filter LP⁴ to the common input circuit 31 and modulate both of the generated waves 35 in the circuit OMD³. The lower side band produced by modulation of the wave of 10,000 cycles passes from circuit 30 selectively through the band filter BF¹ and is impressed upon the west line section ML. 40 The modulated wave produced by modulation of the wave of 23,333 passes selectively through the filter BF² and is impressed on the east section of the line ML. It is seen, therefore, that the attendant may both listen 45 and talk over both sections of the main line ML through the channel C¹ and it is obvious that by plugging into the filters of another channel such as the filters BF³ and BF⁴ of the channel C² and by properly adjusting the condensers 32 and 33 to cause the 50 generation of carrier waves of the frequencies employed on this channel, the attendant can communicate in a similar manner over another channel.

55 Fig. 3 illustrates a portable signaling set of convenient form to which the invention readily lends itself. As in the case of the other figures, the circuit of this figure is intended for use in connection with a carrier system employing different frequencies for opposite directions of transmission, the arrangement commonly met with in the so-called "grouped frequency" systems. It is assumed that at points on a system where 60 the portable set is to be used channel taps

including filters and jacks, such as the jacks J shown on Fig. 2, will be provided and the plug P is designed for insertion into a pair of jacks serving as taps for the two sides of a two-way channel. For communicating 70 over channels employing different frequencies the translating circuit of Fig. 3 is arranged, as in the case of the other figures, to oscillate at two distinct frequencies, and in order to enable communication over any 75 pair of channels of the system the frequencies at which the translating circuit oscillates are readily changed. For this purpose the feed-back connection 41 is shown provided with three different sized condensers 80 42, 43 and 44, any or all of which may be thrown in circuit across the coil 41 by means of the keys shown. These condensers are so proportioned that by pressing certain keys the translating circuit may be made to oscillate at any of the channel frequencies of the 85 system. The feed-back coupling 45 has associated with it other condensers 46, 47 and 48 and has keys, as shown, for selectively throwing these condensers into the circuit 90 so that the translating device oscillates under control of this feed-back circuit also at any of the channel frequencies of the system.

In the circuit of Fig. 3 no low frequency telephone balance is provided as in the other 95 figures but a relay 49, controlled from key K on the hand microphone set comprising receiver R¹ and transmitter T¹, controls, by its armature, the connection of the secondary winding of either feed-back coil 41 or 100 45 so that the translating circuit oscillates at one frequency when the relay is deenergized and at another frequency when the relay 49 is energized provided the capacity included in circuit due to the connection of 105 the condensers 42, 43 and 44 differs from that provided by the connection of the condensers 46, 47 and 48. The filters LP, LP transmit speech frequencies but prevent the transmission of any of the carrier frequencies. 110

In operation the twin plug P is inserted into a pair of jacks of the two one-way channels with which communication is desired and certain of the condensers 42, 43 and 44 115 are connected in circuit to cause the translating circuit to oscillate at the carrier frequency of the channel over which it is desired to receive. Similarly, certain of the condensers 46, 47 and 48 are connected in 120 circuit to cause the translating device to oscillate at the carrier frequency of the transmitting channel. The operator, in listening, allows the key K to remain open and the armature of the relay 49 is, therefore, 125 against its back contact, making the feed-back coil 41 operative to cause the circuit to oscillate at the receiving carrier frequency. Current received from the line passes through the channel tap including 130

the channel filter and jack to which the plug 51 is connected and to the input coil 52, the lowermost filter LP blocking the transmission of this current through its circuit.

5 From the coupling 52 the received side band is impressed upon the translating circuit and due to the interaction between the received side band and the generated wave, voice frequency currents are produced in the output coil 53. These pass through the uppermost of the filters LP to the receiver R¹.

When the operator desires to talk he presses the key K, causing energization of relay 49 which shifts its armature so as to 15 connect the secondary winding of feed-back coil 45 into the grid circuit, causing the translating device to oscillate at the transmitting carrier frequency. Voice currents produced in the circuit of the microphone 20 T¹ pass through the filter LP to the input circuit 52 and modulate the locally produced carrier wave. The resulting side band is transmitted to the coupling 53 and the plug 55 to the jack of the outgoing channel tap.

In the foregoing description of the operation of the portable translating device shown in Fig. 3, it was assumed that the high frequency line was provided with channel taps including channel filters such as are shown in Fig. 2. These filters act in the manner described in connection with other figures to direct the carrier and speech frequencies along their proper paths associated 30 with the translating circuit. In case the line is not provided with channel filters it is still possible to use the translating device of Fig. 3 by inserting the plug P³ into a jack connected directly across the line and 40 without the interposition of any channel filters, although it may be advantageous to have a high pass filter inserted between the jack and the line in the case where the high frequency line serves to transmit an ordinary low frequency telephone conversation in addition to the various carrier transmissions. With the plug P disconnected from the system and the plug P³ connected as described, the relay 56 being deenergized, currents of the frequencies of all of the channels enter the circuit of the translating device through the terminals of the plug P³, the right-hand contacts of relay 56, the incoming connection of the translating circuit to the coil 52, and are impressed on the 50 circuit of the translating device. By the well-known homodyne action the received carrier wave having the same frequency and phase as the locally generated wave, will 55 yield its modulation components, that is, speech currents in the output circuit and these will pass through the uppermost filter LP to the receiver R¹. Each of the other received carrier frequencies will also interact with the locally produced wave, but the

resulting components will have frequencies of the order of the frequency difference between adjacent channels or still higher, and will, therefore, be prevented from passing into the receiving circuit by the associated filter LP. The speech that is received is, therefore, that represented by the modulating of the particular wave of the frequency at which the translating device oscillates when receiving and the speech of this particular channel is selectively received. By tuning the feed-back circuit of the translating device to other carrier frequencies the speech of any other of the channels may similarly be received. The higher frequency components produced in the translating circuit by the interaction of the different channel frequencies are prevented from passing again to the line, since the relay 56 is deenergized and the outgoing circuit from the coil 53 is broken at the left-hand contacts of this relay.

As stated above, the operator presses the key K during the transmitting interval. In case the plug P³ is being used, it is necessary also to close the contact 57 in the circuit of the relay 56 during the talking interval, in order to energize relay 56 and switch the connection of the plug P³ from the receiving side to the transmitting side 95 of the translating circuit. For convenience in the arrangement of the drawing, the contact 57 is shown apart from the key K, but in practice the two springs of contact 57 would be arranged behind the button of the key K, but suitably insulated therefrom, in such a manner that when the key is depressed the contact 57 is closed, such double contact key arrangements being common and well-known in the art. Having depressed 100 key K and closed contact 57 causing energization of relays 49 and 56, the operator proceeds to talk against the transmitter T¹. With the relay 49 energized the feed-back coil 45 becomes effective to cause the translating device to oscillate at the transmitting frequency and speech currents from the circuit of the transmitter T¹ pass through the coil 52 and modulate the wave of the transmitting frequency. The resulting modulated carrier wave is transmitted through the coil 53, the left-hand contacts of relay 56 now closed, the terminal of plug P³ and of the jack with which it is assumed to be connected, and to the main line. The right-hand contacts of the relay 56, being now open, the outgoing current is prevented 110 from passing again into the input circuit of the translating device.

It will be obvious that the variable condensers in the circuit OMD^a, for example, may be replaced if desired by keys and different fixed or variable capacities arranged as in the circuit of Fig. 3, or vice versa.

Further, it is to be understood that the

circuits shown and described are merely illustrative of the preferred forms of practising the invention, but that neither the drawing nor the description should be taken as limiting the invention, the scope of which is defined in the claims.

What is claimed is:

1. A combined oscillator-modulator comprising a self-oscillating vacuum tube modulator comprising a pair of space discharge paths connected in balanced relation with respect to the incoming and outgoing circuits having a pair of feed-back circuits differently tuned to enable it to oscillate at two different carrier wave frequencies.
2. A combined oscillator-modulator comprising a self-oscillating vacuum tube modulator comprising a pair of space discharge paths connected in balanced relation with respect to the incoming and outgoing circuits arranged to oscillate at two different carrier wave frequencies in combination with means for impressing thereon signaling waves to combine with both carrier waves.
3. A combined oscillator-modulator comprising a self-oscillating vacuum tube modulator arranged to oscillate at two different carrier wave frequencies and having means for impressing signaling voltage variations thereon to produce side band frequency components of both of said waves, said oscillator-modulator having a balanced circuit arrangement to suppress transmission of the unmodulated carrier components of both waves, but to transmit the side band components.
4. A combined oscillator-modulator comprising a pair of cathode-grid-anode tubes connected in balanced or push-pull relation and a plurality of selective feed-back circuits for impressing different frequencies on the grids to cause the tubes to oscillate at a plurality of carrier wave frequencies and means to impress signal voltage variations on the grids to modulate the said carrier waves.
5. A translating circuit comprising a vacuum discharge tube modulator comprising a pair of space discharge paths connected in balanced relation with respect to the incoming and outgoing circuits arranged to oscillate simultaneously at a plurality of wave frequencies and means for impressing signal voltage variations on said modulator to produce combination frequencies with each of the generated waves.
6. In a signalling system a combined oscillator-modulator comprising a self-oscillating modulator arranged to oscillate at a plurality of different wave frequencies, means to impress signal voltage variations on said modulator to produce side band components with each of the generated waves, and an outgoing circuit, said oscillator-modulator comprising a pair of space discharge paths

connected in balanced relation with respect to the incoming and outgoing circuits arranged to suppress the transmission of the unmodulated component of each of said generated waves to said outgoing circuit but to transmit the side band components thereto.

7. A two-way translating circuit for a two-way channel employing different carrier frequencies for transmitting and receiving, comprising a self-oscillating modulator having input and output circuit branches connected to the respective sides of said channel, said modulator having a pair of feed-back circuits differently tuned to enable it to oscillate at two different frequencies corresponding respectively to the receiving and transmitting channel frequencies.

8. A combined oscillator-demodulator comprising a self-oscillating vacuum tube demodulator comprising a pair of discharge paths connected in balanced relation with respect to the incoming and outgoing circuits arranged to oscillate simultaneously at two different carrier wave frequencies.

9. In a carrier signaling system a two-way translating circuit comprising a self-oscillating vacuum tube modulator-demodulator having an input and an output circuit, a signaling-frequency and a carrier-frequency incoming circuit each connected to the input circuit, a signaling-frequency and a carrier-frequency outgoing circuit each connected to the output circuit, the outgoing carrier frequency being different from the incoming carrier frequency, said vacuum tube circuit being arranged to oscillate at both of said carrier frequencies.

10. A two-way translating circuit as claimed in claim 9, a signaling-frequency filter being included in each of said incoming and outgoing signaling-frequency circuits and a carrier-frequency filter being included in each of said incoming and outgoing carrier-frequency circuits, each of said latter two filters being arranged to pass freely the carrier frequency of the circuit in which it is connected, but to block transmission of current of the signaling frequency of the other carrier frequency.

11. In combination a self-oscillating vacuum tube modulator-demodulator circuit having an input and an output circuit, a signaling frequency circuit connected to both said input and said output circuits, the connection to each of said two last-mentioned circuits containing a signaling-frequency filter, a carrier line connected to both said input and said output circuits, the connections to said last-mentioned circuits including each a filter of a different carrier frequency, said tube circuit being arranged to oscillate at both of said carrier frequencies.

12. An arrangement as claimed in claim 11, said modulator-demodulator circuit hav-

- ing a balanced circuit arrangement to suppress the unmodulated carrier component of each of said carrier waves, but to permit transmission of side band frequency components.
13. The combination with a mid-line repeater for a multiplex carrier line employing carrier waves of different frequencies for oppositely directed transmissions, of a monitoring circuit comprising a two-way self-oscillating translating device having an input and an output circuit, channel taps at said repeater, switching means for connecting said input circuit to each of two oppositely directed channels, means to adjust said translating device to oscillate at the frequencies of both of said channels, a telephone set connected to said output circuit and a voice filter included in the connection to said set.
14. The combination with a mid-line repeater for a multiplex carrier line employing carrier waves of different frequencies for oppositely directed transmissions, of a monitoring circuit comprising a two-way self-oscillating translating device having an input and an output circuit, channel taps at said repeater switch, means for connecting said output circuit to each of two oppositely directed channels, means to adjust said translating device to oscillate at the frequencies of both of said channels, a telephone set connected to said input circuit and a voice filter included in the connection to said set.
15. A combined oscillating and modulating circuit comprising a self-oscillating vacuum tube circuit having means for generating a carrier wave for transmission and a wave of a different carrier frequency for receiving and having means for impressing 40 signaling voltage variations thereon for modulating the first mentioned carrier wave for transmission and for impressing received wave modulations thereon for interacting with the second mentioned carrier 45 wave to reproduce signal variations.
16. In a combined oscillator-modulator-demodulator system, incoming and outgoing circuits, a pair of space discharge paths connected in balanced relation with respect to 50 the incoming and outgoing circuits, means for causing said system to generate oscillations of carrier frequency, and means to impress on said system modulating waves for controlling said oscillations and modulated waves to be demodulated.
17. A translating system common to an input and an output circuit, said translating system comprising a combined oscillator-modulator-demodulator comprising a 60 pair of space discharge paths connected in balanced relation with respect to said input and output circuit, arranged to oscillate simultaneously at two different carrier frequencies and means for impressing voltage 65 variations on said discharge paths to produce combination frequencies with each of said carrier frequencies.
- In witness whereof, I hereunto subscribe my name this 15th day of March A. D., 70 1922.
- JOSEPH W. HORTON.
